UNITED STATES PATENT OFFICE.

ALEXANDER McL. NICOLSON, OF NEW YORK, N. Y., ASSIGNOR TO WESTERN ELECTRIC COMPANY, INCORPORATED, OF NEW YORK, N. Y., A CORPORATION OF NEW YORK.

PIEZO-ELECTRIC DEVICE AND METHOD OF PRODUCING THE SAME.

Application filed August 6, 1923. Serial No. 655,800.

To all whom it may concern:

Be it known that I, ALEXANDER McL. NICOLSON, a subject of the King of Great Britain, residing at New York, in the county 5 of New York, State of New York, have invented certain new and useful Improvements in Piezo-Electric Devices and Methods of Producing the Same, of which the following is a full, clear, concise, and exact description.

10 This invention relates to piezo-electric devices and methods of producing the same, and aims to provide sensitive, efficient, simple and durable devices of that character, for translating electrical variations into 15 mechanical force variations, and vice versa, such devices being useful in, for instance, the transmission and reception of telephone currents and the phonographic recording and reproduction of sound waves.

20 In accordance with the invention a piezo-electric crystal, preferably a Rochelle salt crystal having the composite or hour-glass structure and having orthogonal electric poles, such as is described in my article on 25 "The piezo-electric effect in the composite Rochelle salt crystal," Proceedings of the American Institute of Electrical Engineers, November, 1919, is provided with electrodes or electrically conducting, charge collecting

30 means in contact with the parts of the crystal which are oppositely electrified when the crystal is stressed, one of the charge collecting means being preferably in intimate contact with the interior of the crystal. For 35 example, the means for collecting the charges from the pyramidal poles or hour-glass shaped portions of the crystal may be an electrical conductor or conductors within or passing through those portions and cutting various imaginary planes perpendicular 40 to the principal axis of the crystal, that is, planes parallel to and lying between the basal planes of the crystal.

45 At the place where this interior electrode or the lead for connecting it in circuit passes through the surface of the crystal it may occupy a very small portion of that surface, and therefore it is easy to insure that the leakage resistance along the surface of the 50 crystal from this interior electrode to the charge collecting conductor of opposite sign will be maintained high, as for instance, by bringing the interior conductor, or its lead, through the surface of the crystal at a point

distant from the conductor of opposite sign, 55 or by bringing the interior conductor or its lead through the surface in an insulating tube or covering, or by employing both of these features.

Further, by reason of the fact that this 60 electrode is within the crystal, intimate contact may be easily maintained between the electrode and the crystal without any necessity of employing adhesive or clamping means to attach the electrode to the crystal. 65

Fig. 1 of the accompanying drawings is a side elevation of a loud speaking telephone receiver embodying one form of the invention; Fig. 2 is a front elevation of Fig. 1; Fig. 3 is a side elevation of a crystal having 70 an interior electrode of a different form from that shown in Fig. 1; Fig. 4 is a rear elevation of Fig. 3; Fig. 5 is a perspective view of a crystal growing about an interior electrode; and Fig. 6 is a fragmentary view 75 of the crystal of Fig. 5 which has been furnished with an exterior electrode and means for increasing surface leakage resistance between that electrode and the lead for the interior electrode. 80

Referring especially to Figs. 1 and 2, a piezo-electric crystal 10 having the composite structure referred to above is mounted on a base 11. The crystal may be produced by methods such as, for instance, 85 those described in the above mentioned A. I. E. E. publication or in my Patents No. 1,414,370, May 2, 1922, method of making piezo-electrical crystals, and No. 1,438,965, Dec. 19, 1922, piezo-electric devices and 90 methods of producing the same. Attached to the upper end or upper basal plane of the crystal is an arm 12 which carries a diaphragm 13 to be vibrated by arm 12 in response to twisting of the crystal about its principal, or vertical axis. The crystal may be caused to twist by applying an electro-motive force to a girdle electrode 14 and an electrode 15 which is imbedded in the crystal. Conversely, electromotive force may be 100 generated between these electrodes by twisting the crystal, as for instance by causing sound waves to impinge upon the diaphragm 13.

The girdle electrode is shown as of the 105 character described in the A. I. E. E. publication mentioned above, and also described in the above mentioned Patent No. 1,438,965.

The pyramidal, or hour-glass shaped poles of the crystal are designated 16 and 17, and are indicated in the drawing by dotted lines 18 converging toward the seedling 19 from which the crystal is grown. The interior electrode 15 preferably passes through the pyramids 16 and 17 in the general direction of the principal axis of the crystal and extends substantially the whole length of the crystal, so that it will cut imaginary planes passed perpendicular to the crystal axis and lying between the apices of the pyramids and points near the ends of the crystal. The portion of pyramidal pole lying between any one of these planes and the apex of the pyramidal pole may be regarded as a pyramidal pole having that plane as its basal plane, and the electrode 15 passes through and contacts with a great number of such planes, thus collecting the electrical charges appearing on them when the crystal is stressed, and conducting such charges to the outside of the crystal by means of the lead 25 connected to or forming an extension of the conductor 15, it being understood, of course, that lead 25 may be connected to one terminal of a receiving apparatus (not shown) the other terminal of which may be connected to a lead 27 brought from the girdle electrode 14 of the crystal. When the crystal device is used as a receiver, the source of electro-motive force (not shown) from which it is to be operated is connected between leads 25 and 27, and the conductor 15 acts as a charging means, instead of as a collector of electrical charges.

In order to insert the conductor 15 in the crystal, a hole may be drilled in the crystal. The electrode 15 is preferably of some form designed to have intimate contact with the surrounding crystal, and may be, for instance, a column of mercury, saturated 45 Rochelle salt solution, or graphite, or a wire 30 preferably surrounded by tinfoil pellets, graphite, conducting liquid, or other electrically conducting material 31 for insuring that the resistance between the wire and the crystal will be low. The tinfoil pellets, if used, may be tamped in around the wire.

Where the wire 30 passes through the surface of the crystal it may have a rubber covering or other electrical insulation, as indicated at 33, and a tube 35 of quartz or the like having high surface leakage resistance may also surround this portion of the wire 30. Insulating material in the form of a cement is preferably placed around the elements 35, 33 and 30 where they pass through the crystal surface, as indicated at 37. A suitable cement may be made by fusing crystalline sodium potassium tartrate. The fused mass may be allowed to cool below the fusion temperature without

immediate setting, but when thus super-cooled will quickly set upon agitation, such for instance as that incident to its application to the surfaces which are to be joined. To insure that the cement will have a high 70 resistivity, it should, while in the fused state, be heated sufficiently long and at a sufficiently high temperature to decrease the water content somewhat, but if heated too long or at too high temperature, the cement, after 75 hardening, will not have sufficiently strong cohesive and adhesive powers. The cement is preferably also coated over the ends of the crystal, as indicated at 40, to increase the surface leakage resistance between the 80 tube 35 and the girdle electrode 14. It will be seen that any leakage currents flowing from lead 25 over the surface of insulation 33, 35, and 40, and thence over the surface of the crystal to electrode 14, encounter high 85 resistance, so that even in humid weather any effect of this surface leakage resistance in shunting the source or load connected across leads 25 and 27 will be small. This cement and its use in combination with a 90 piezo-electric structure forms no part of the present invention but is claimed in my pending application, Serial No. 740,746, filed September 30, 1924.

The cement coatings 40 on the top and 95 bottom ends of the crystal also reduce leakage, over the surface of the crystal, between the basal planes (or bases of the pyramidal portions) of the crystal and the remaining 100 crystal surfaces, because these coatings reduce flow of charge along the surfaces of the basal planes, since the coatings protect the basal planes from exposure to the moisture of the atmosphere, and since the exposed surfaces of the coatings collect 105 relatively little moisture from the air and have high surface leakage resistance even in humid weather.

The cement coating 40 at the upper end of 110 the crystal may also be used to cement the arm 12 to the crystal, as indicated in the drawing; and similarly, the cement coating 40 for the lower end of the crystal may be used to cement the crystal in a groove 45 in the base 11.

Fig. 3 shows a crystal 10' of the same character as the crystal 10 of Figs. 1 and 2, and having a girdle electrode 14' of the same general character as the girdle electrode 14 of crystal 10; but the crystal 10' has two internal electrodes 15' instead of the internal electrode 15 of crystal 10. Two holes are drilled in the crystal 10' for the reception of the electrodes 15', each hole extending 120 from the vicinity of the seedling 19' in the general direction of the axis of one of the pyramidal portions of the crystal, as indicated by the drawing. Thus, each electrode 15' intersects imaginary planes passed perpendicular to the crystal axis and lying be- 125

tween the apices of the pyramids and a point near one end of the crystal.

The electrodes 15' may be of construction similar to the electrode 15. At the adjacent 5 ends of the electrodes 15' the crystal 10' may have a recess made therein and filled with cement of the character referred to above, as indicated at 50. In this cement may be anchored a binding post 51 to the 10 inner end of which the electrodes 15 may be soldered or otherwise electrically connected. A lead 25' corresponding to the lead 25 in Figs. 1 and 2, may be connected to post 51. The girdle electrode 14' is cut away around 15 the edge of the cement filled recess, as indicated at 55, so that any leakage current flowing over the surface of the cement 50 between the girdle pole 14' and the leads 25' will encounter high leakage resistance on the 20 exposed surface of the cement 50 even in humid weather. The ends of the crystal 10' may, of course, be capped with cement, as in the case of the crystal 10, and the crystal 10' may be mounted in any suitable manner, as 25 for instance in the manner in which crystal 10 is mounted. To put the electrodes 15' in the crystal 10', the crystal may be turned with its face downward, mercury 31' may be poured into the holes which have been 30 drilled for it, wires 30' inserted in the mercury, and cement 50 placed in the recess provided therefor. The wire should preferably be of such character that it will not be easily corroded by the surrounding conductor. Thus, if the surrounding conductor 35 is mercury, for instance, then the wire may be of nickel or iron, for example.

Fig. 5 shows how a crystal 60 may be grown about an electrode 61 so that the electrode will be an interior electrode. The electrode may be given various forms. As 40 shown, it consists of a wire like the wire 30 shown in Fig. 1, but having arms 65 extending outwardly therefrom and lying 45 within the pyramidal portions of the crystal. These arms assist the central wire to collect the charges generated in the pyramidal poles when the crystal is stressed. The crystal is grown in the manner referred 50 to above, except that the electrode 61 is laid upon the seedling in the position shown, when the seedling is placed in the mother liquor. As the crystal grows it envelops the electrode 61 in the pyramidal portions of 55 the crystal. The girdle electrode used with this crystal is indicated at 70 in Fig. 6 and may be like that of the crystal 10 of Figs. 1 and 2.

In order to increase the surface leakage 60 resistance between the electrode 61 and the girdle electrode 70, cement of the character referred to above may be placed around the electrode 61 where it passes through the surface of the crystal, as indicated at 75 65 in Fig. 6; or the electrode 61 may be brought

out by means of a cement plug and a binding post, corresponding to elements 50 and 51 of Fig. 3; or the electrode may be brought out through insulating means of the character shown at 33 and 35 in Fig. 70 75 1. The ends of the crystal 60 may be capped with cement as in the case of the crystal 10, and the crystal 60 may be mounted in any suitable manner, for instance, as the crystal 10 is mounted.

What is claimed is:

1. A crystal having means including an electrode in the interior of the crystal, for connecting said crystal in an electric circuit.

2. A piezo-electric crystal having means including an electrode in the interior of the crystal, for connecting said crystal in an electric circuit.

3. A sodium potassium tartrate crystal 85 having a pyramidal pole, and an electrode extending within said pole.

4. A piezo-electric crystal comprising two portions oppositely electrified when said crystal is stressed, and an electrode 90 embedded in one of said portions.

5. A piezo-electric crystalline structure comprising a pyramidal pole, a girdle pole about said pyramidal pole, and an electrode 95 in the interior of said pyramidal pole.

6. A piezo-electric crystal comprising a girdle pole and a pole surrounded thereby, and an electrode interior to said last mentioned pole and emerging from said crystal 100 at a point remote from said girdle pole.

7. A piezo-electric crystal having two adjacent poles of opposite sign, an electrode interior to one of said poles and having a portion extending through the surface of said crystal and insulated from said crystal. 105

8. A crystal having an interior electrode, and means for insulating a portion of said electrode from the surface of said crystal.

9. The method of obtaining a crystal with 110 an interior electrode which comprises growing the crystal about the electrode.

10. The method of making a piezo-electric crystal device which comprises growing a sodium potassium tartrate crystal having pyramidal poles and so locating an electrode 115 with respect to the growing crystal as to cause the electrode to be substantially enveloped in the pyramidal poles by the growth of the crystal.

11. A telephone transmitter and receiver 120 comprising a piezo-electric crystal having an interior electrode, an electrode of opposite sign, and means for transmitting elastic vibrations between said crystal and a surrounding medium capable of propagating 125 such vibrations.

In witness whereof, I hereunto subscribe my name this 3rd day of August, A. D., 1923.

ALEXANDER McL. NICOLSON.
